Patented Mar. 29, 1966

204,208

COMBINED RADIO-RECEIVER, RECORD PLAYER AND TELEVISION RECEIVER

Ludovico Marchese, 1 Piazza Tavallini, Casale
Monferrato, Italy

Filed Sept. 2, 1964, Ser. No. 81,566

Term of patent 3½ years

(Cl. D56—4)

Fig. 1

Fig. 2

Fig. 3

FIG. 1 is a perspective view of a combined radio-receiver, record player and television receiver, showing my new design.

FIG. 2 is a top plan view; and

FIG. 3 is a side elevational view thereof.

I claim:

The ornamental design for combined radio-receiver, record player and television receiver, as shown.
